UNITED STATES PATENT OFFICE.

ALBERT E. WEAVER, OF INDIANAPOLIS, INDIANA, ASSIGNOR, BY MESNE ASSIGNMENTS, TO IRA T. SWARTZ, TRUSTEE, OF INDIANAPOLIS, INDIANA.

CARBURETOR.

Application filed August 8, 1921. Serial No. 490,612.

This invention relates to a carburetor construction, and the prime feature of the invention is the provision, in connection with the usual float chamber and dome, of an 5 elongated cylindrical body portion for forming a mixing chamber, said body portion having a wedging action with parts of the carburetor to form a seal-tight joint between the parts.

10 A further feature of the invention is in so connecting the dome portion of the carburetor with the float containing bowl portion thereof, that various adjustments may be had for positioning the dome portion and 15 the bowl portion of the carburetor for engagement with the parts to which they are attached and at the same time leave the dome and bowl portions so spaced that the body portion will be securely clamped and locked 20 between the dome and bowl portions.

Other objects and advantages will be hereinafter more fully set forth and pointed out in the accompanying specification.

In the accompanying drawing

25 The figure is a vertical central sectional view through the carburetor.

Referring to the drawing, 1 indicates the bowl portion of the carburetor in which is mounted a float 2, said float controlling the 30 admission of fuel into the bowl. Cooperating with the bowl 1 is a dome 3, the upper end of which is provided with a coupling member 4 through the medium of which the carburetor is attached to the usual form of 35 intake manifold (not shown). Between the bowl 1 and dome 3 is a cylindrical body portion 5 which is preferably elongated, the upper surface of the bowl 1 having a flange 6 thereon with which the lower end of the 40 body portion 5 engages, and in order to form a perfect seal between the body portion and the flange, the outer face of the lower end of the body portion and the inner face of the flange 6 are oppositely tapered, as shown 45 at 7, so that when the lower end of the body portion is forced against the flange they will wedge together and prevent any possibility of leakage at this point.

The lower end of the dome 3 is likewise 50 provided with a flange 8 for the reception of the upper end of the cylindrical body portion 5, the upper end of the body portion fitting snugly within the flange and abutting against a shoulder 9 formed within the dome.

55 The three elements of the carburetor are

locked together through the medium of a tube 10, the lower end of the tube being threaded into a collar 11 on the bowl 1, while the upper end of the tube is threaded into a discharge opening 12 through the dome 3, a 60 lock nut 13 being employed for locking the tube against rotation after it has been properly set within the collar 11. The lower end of the tube 10 is preferably provided with threads having a pitch which is less than 65 the pitch of the threads at the upper end of the tube, so that substantially a half turn of the tube into or out of the collar will permit a quarter turn of the dome onto the upper end of the tube. By arranging the parts in 70 this manner a minute adjustment between the bowl and dome may be had and which will permit the coupling member 4 or the intake opening 14 for the bowl to be positioned at various angles with respect to each other, 75 for proper connection with their respective parts without interfering with the perfect connection or seal between the ends of the cylindrical body portion and the bowl and dome respectively.

80 In carrying out this feature of the invention, if it is found that either the coupling member 4 or the opening 14 are not properly positioned to engage with their respective parts, the dome 3 is removed, the lock nut 13 loosened and the tube 10 then rotated and so set that when the dome is again engaged with the end of the tube 10 and turned thereon until the cylindrical body portion is securely clamped between the 85 dome and bowl, the coupling member 4 or the opening 14 will be so located with respect to their former positions that they will readily connect with their respective parts. In this manner the coupling member 90 4 may be turned to any degree of angularity with respect to the opening 14, that may be desired for properly connecting these parts to the parts of the motor, and this operation is accomplished without affecting 95 any of the operating parts of the carburetor.

Having thus fully described my said invention, what I claim as new and desire to secure by Letters Patent, is:

100 1. In a carburetor, an upright casing comprising a lower bowl portion providing a reservoir for liquid fuel, a cover having a passage to register with an intake manifold and threads at the lower end of said passage, a cylindrical body between the bowl and the 105 110

- cover, an air intake pipe on the bowl having an internally threaded portion coaxial with the passage in the cover but having a thread of different pitch, a pipe section having its ends threaded to correspond to the threads on the bowl and cover, and providing therewith an air passage through the carburetor, means for injecting mingled fuel and air into said passage, and a locknut on said pipe connection whereby the bowl and cover may be fixed in various angular positions with reference to each other while forming a tight connection with the body portion, substantially as set forth.
2. In a carburetor, an upright casing comprising a lower bowl portion providing a reservoir for liquid fuel, a cover having a passage to register with an intake manifold and threads at the lower end of said passage, a cylindrical body between the bowl and the cover, a valved intake pipe on the bowl having an internally threaded portion coaxial with the passage in the cover, a pipe section having threads at its ends corresponding to those on the bowl and cover and providing therewith a passage through the carburetor, said section serving as the air passage through the carburetor and a locknut on the pipe whereby the bowl and cover may be fixed in various angular positions with reference to each other while forming a tight connection with the body portion, substantially as set forth.
3. In a carburetor, an upright casing comprising a lower bowl portion providing a reservoir for liquid fuel, a cover having a passage to register with an intake manifold and threads at the lower end of said passage, a cylindrical body between the bowl and the cover, a valved intake pipe on the bowl having an internally threaded portion coaxial with the passage in the cover, and a pipe section having threads at its ends corresponding to those on the bowl and cover and providing with said intake pipe an air pas-

sage through the carburetor, substantially as set forth.

3. In a carburetor, an upright casing comprising a lower bowl portion providing a reservoir for liquid fuel, a cover having a passage to register with an intake manifold and threads at the lower end of said passage, a cylindrical body between the bowl and the cover, a valved intake pipe on the bowl having an internally threaded portion coaxial with the passage in the cover, a pipe section having threads at its ends corresponding to those on the bowl and cover and providing therewith a passage through the carburetor, said section serving as the air passage through the carburetor and a locknut on the pipe whereby the bowl and cover may be fixed in various angular positions with reference to each other while forming a tight connection with the body portion, substantially as set forth.

In witness whereof, I have hereunto set my hand at Indianapolis, Indiana this thirtieth day of July, A. D. nineteen hundred and twenty-one.

ALBERT E. WEAVER.
